UNITED STATES PATENT OFFICE

LEO R. INGHRAM, OF CEDAR GROVE, WEST VIRGINIA

COLLAPSIBLE TUBE CLOSURE

Application filed March 8, 1932. Serial No. 597,573.

The present invention relates to a closure for collapsible tubes of the type in widespread use at present for containing substantially semi-fluid products such as tooth paste and shaving cream and has for its primary object to provide, in a manner as hereinafter set forth, a closure embodying a novel construction, combination and arrangement of parts through the medium of which said closure will be caused to open by the pressure of the contents of the tube thereagainst when said tube is squeezed and which will immediately close when the pressure is removed.

Other objects of the invention are to provide a tube closure of the aforementioned character which will be simple in construction, strong, durable, compact, efficient and reliable in use and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:

Figure 1 is a view in side elevation showing a closure constructed in accordance with this invention in position on a tube.

Figure 2 is a view in vertical section, taken substantially on the line 2-2 of Figure 1.

Figure 3 is a view in horizontal section, taken substantially on the line 3-3 of Figure 1.

Figure 4 is a view in horizontal section, taken substantially on the line 4-4 of Figure 2.

Referring now to the drawing in detail, it will be seen that the reference numeral 1 designates the body portion of a conventional collapsible tube, and 2 is the shoulder portion of said tube from which the outlet neck 3 rises.

The embodiment of the invention which is illustrated in the drawing comprises a cylinder 4 having a reduced neck 5 on its lower end engaged in the tube neck 3 and secured therein by a key 6. At its lower end, the

neck 5 terminates in an internal flange 7. The cylinder 4 is open at its upper end and said cylinder is provided, at an intermediate point, with a port 8.

Slidably operable in the cylinder 4 is a valve 9 which controls the port 8. Depending from the lower end of the valve 9 is a reduced shank 10 which, when the valve is in closed position, is engaged in the neck 5.

Extending diagonally into the shank 10 is a slot 11 for connecting one end of a coil spring 12 to the valve. The other end of the spring 12 is connected to a bar 13 which is fixed transversely in the lower portion of the neck 5.

Normally, the valve 9 is yieldingly secured in closed position over the port 8 by the spring 12. However, when the tube 1 is squeezed, the contents of said tube exert pressure against the lower end of the valve 9, thereby actuating said valve. Thus, the valve 9 is actuated to uncover the port 8 through which the contents of the tube may now pass. As soon as the pressure is eliminated, the spring 12 returns the valve 9 to its original position, thus immediately closing and sealing the tube.

It is believed that the many advantages of a tube closure constructed in accordance with the present invention will be readily understood, and although the preferred embodiment of the invention is as illustrated and described, it is to be understood that changes in the details of construction and in the combination and arrangement of parts may be resorted to which will fall within the scope of the invention as claimed.

What is claimed is:

1. A tube closure comprising a cylinder having a port at an intermediate point therein, a reduced neck on one end of the cylinder engageable in the tube for mounting the cylinder in position thereon, the other end of the cylinder being open, a valve slidably operable in the cylinder for controlling the port, a reduced shank on one end of the valve engageable in the neck, a bar mounted transversely in the neck, and a spring having one end connected to the bar and its other end con-

nected to the shank for yieldingly securing the valve in operative position.

2. A tube closure comprising a cylinder, a reduced neck on one end of the cylinder engageable in the tube for mounting the cylinder in position thereon, an internal flange on the neck, a bar mounted transversely in the neck adjacent the flange, the other end of the cylinder being open, said cylinder having a 10 port at an intermediate point therein, a valve slidably operable in the cylinder, a reduced shank on one end of the valve engageable in the neck, and a coil spring having one end connected to the bar and its other end connected to the shank for yieldingly securing the valve in operative position.

3. A tube closure comprising a cylinder, a reduced neck on one end of the cylinder engageable in the tube for mounting the cylinder 20 in position thereon, the other end of the cylinder being open, said cylinder having a port at an intermediate point therein, an internal flange on the neck, a bar mounted transversely in the neck adjacent the flange, means for 25 anchoring the neck in the tube, a valve slidably operable in the cylinder for controlling said port, a reduced shank on one end of the valve engageable in the neck, said shank having an inclined slot extending thereinto from 30 one side thereof, and a coil spring having one end connected to the bar and its other end engaged in the slot for connection with the shank for yieldingly securing the valve in operative position.

35 In testimony whereof I affix my signature.
LEO R. INGHRAM.
